MUSICAL TOY

Thomas I. Nakano, Papaikou, Territory of
Hawaii

Application April 25, 1940, Serial No. 331,637

10 Claims. (Cl. 46—174)

This invention relates to an improved sounding or audible toy having sounding means actuated by revolving a body member in which said sounding means is disposed with said body member forming a resonant chamber for the sounding means.

More particularly, it is an object of this invention to provide an audible toy including a hollow body member adapted to be revolved by the operation of a cord which is connected at its ends to the ends of said body member for actuating sounding means disposed within the body member.

Still a further aim of the invention is to provide a toy of the character heretofore described, the hollow body portion or shell of which may be shaped to simulate a football, dirigible, torpedo or other devices having similar configurations or shapes.

Other objects and advantages of the invention will hereinafter become more fully apparent from the following description of the drawings, which illustrate a preferred embodiment thereof, and wherein:

Figure 1 is a side elevational view of a preferred form of the invention.

Figure 2 is a longitudinal, central sectional view of the same, with the operating cord removed.

Figure 3 is a transverse sectional view taken substantially along the plane of the line 3—3 of Figure 2,

Figure 4 is an enlarged fragmentary sectional view of the central portion of the body member illustrating a modified form of joint or seam for connecting the sections thereof.

Figure 5 is a view similar to Figure 2 of another modified form of the invention.

Figure 6 is a transverse sectional view taken substantially along the plane of the line 6—6 of Figure 5,

Figure 7 is a side elevational view of another form of the body member or shell.

Figure 8 is a transverse sectional view taken substantially along the plane of the line 8—8 of Figure 7,

Figure 9 is a fragmentary side elevational view of the same, showing the connecting tongues or clips in released position, and

Figure 10 is an enlarged fragmentary view showing portions of the sections of the body members separated and showing the tongues or clips in a released position.

Referring more particularly to the drawings wherein like reference characters designate like

or corresponding parts throughout the different views, 10 designates generally a preferred embodiment of an improved musical or sounding toy which includes an elongated hollow body member or shell 11, provided with tapered ends 12, through which extends a shaft 13 the end portions 14 of which protrude beyond the ends of the shell 11. A cord 15 has its ends securely fastened in grooves 16, of the end portions 14, and is provided with a knot 17 intermediate of its ends. One or more sounding devices 18, such as bells or chimes are adapted to be mounted in the hollow body member of shell 11 and secured therein by means of fastenings 19 to the shaft 13 and/or the shell 11, as best seen in Figure 3. The body member or shell 11 may be of a variety of shapes to simulate various devices or articles such as footballs, dirigibles and torpedos, the shell 11, disclosed in Figures 1 to 3, being intended to simulate a torpedo and being provided with a propeller 20 rotatably mounted on one of the end portions 14.

To operate toy 10, knot 17 is grasped to support the body member of shell 11 substantially in a horizontal position after which body member or shell is revolved to wind the ends of the cord 15 onto the tapered ends 12. The body member 11 is then released and permitted to drop and in so doing, the ends of the cord 15 will be unwound therefrom for revolving the body member 11. Up and down motion on the intermediate portion of the cord 15 will cause the body member or shell 11, due to its momentum, to continue to revolve to wind and unwind the ends of the cord, in opposite directions, back and forth onto and from the tapered ends 12 of the body member 11. This motion may be continued indefinitely and will actuate the sounding devices 18 to produce sound which will be varied by the speed or rotation of the body member 11 and which will be amplified by the member 11 which will form a resonator therefor. The rotation of the body member 11 will also revolve the shaft 13 to thereby cause the propeller 20 to revolve therewith or relatively thereto.

The shell 11, as seen in Figures 1 to 3, is preferably formed of two corresponding metallic sections 21, each of which is preferably formed of sheet metal, or the like, and provided with an internal longitudinal seam or joint 22, as best seen in Figure 3, which is formed by turning one edge of the material outwardly and back upon itself to form a hook 23, which is off-set inwardly, and by forming an inwardly turned 55

hook 24 by turning the opposite corresponding edge of the material inwardly and back upon itself, after which the hook shaped edges are interlocked to form the internal joint or seam 22. The two sections 21 are connected at their enlarged ends to each other by means of a joint or seam 25. The joint or seam 25 is formed by providing the open end of one of the sections 21 with an annularly inwardly opening channel 26 10 to receive an outwardly projecting annular flange 27 on the other section for interlocking the sections. The seam or joint 25 may be made permanent by a ring of solder or by a series of spot welds as at 28.

15 In Figure 4, a slightly modified form of body member, designated 11' is shown, wherein the sections 21' are connected to each other by means of an internal joint or seam 29 in lieu of the joint or seam 25, which corresponds to 20 the seams or joints 22, as seen in Figure 3, and as heretofore described.

Another form of the invention is shown in Figures 5 and 6, wherein a body member or shell 30 is formed from two cone shaped sections 31, 25 the enlarged ends of which are disposed in overlapping relationship as is seen at 32, for engaging the periphery of a disk 33 which is fixed to a shaft 34, intermediate of its ends. The overlapping portions 32 are secured to the disk 33 by 30 means of a plurality of fastenings 35. The shaft 34 is also provided with tapered hub portions 36, adjacent its ends which fit in the remote, restricted ends of the conical sections 31 and which are secured thereto by fastenings 37. The 35 conical sections 31 may be made of any suitable material, such as cardboards, paper or metal. On either side of the disk 33, the shaft 34 is provided with one or more sounding devices 38, and the end portions of the shaft 34, which project beyond the body member or shell 30, are 40 grooved at 16, similarly to the shaft 13. A propeller 20 is mounted on one of the ends of the shaft 34.

In Figures 7 to 10, still another embodiment 45 of the toy is illustrated comprising a hollow body portion or shell 38, which is preferably formed of metal and which includes two corresponding sections 39, each of which extends the length of the shell 38. Sections 39 are provided with outwardly projected flanges 40 which are disposed 50 in abutting engagement to form the shell or hollow body member 38. The flanges 40 are provided with tongues or clips 41. The clips 41 of each flange 40 are adapted to be bent around the outer side of the other flange 40 to clamp the shell sections 39 together. The body member or shell 38 is not provided with a shaft, such as the shafts 13 or 34, but in lieu thereof is provided with restricted shank portions at its ends, as seen at 55 42, which are provided with grooves 43, corresponding to the grooves 16 for receiving the ends of an operating cord such as cord 15, not shown in Figures 7 to 10.

The forms of the invention as shown in Figures 65 5 to 10 are adapted to be operated in the same manner as heretofore described in regard to the toy 10, and in the form as shown in Figures 7 to 10, sounding devices, such as those shown at 18 in Figures 2, 3 and 5 may be secured within the shell 38.

Various modifications and changes in the various forms of the invention are contemplated and

may obviously be resorted to as only preferred embodiments thereof have been disclosed.

I claim as my invention:

1. A toy comprising an elongated hollow body portion, having tapered ends, a cord secured at 5 its ends to the ends of said body portion, and sound producing devices secured in said body portion, said body portion being revolved for winding the ends of the cord on to the ends of the body portion and for unwinding them therefrom and the rotation of said body portion actuating said sound producing devices.

2. A toy comprising an elongated shell, of substantially circular cross section having tapered ends, shaft portions projecting from said ends, 15 a cord having its ends connected to the ends of said shaft portions, and noise producing means mounted in said shell and actuated by the rotation thereof.

3. A toy as in claim 2, said shell being formed 20 of end sections connected at their enlarged, adjacent ends, one of said sections having an annular inwardly open channel, and said other section having an annular outwardly projecting flange for engaging said channel for interlocking 25 the sections.

4. A toy as in claim 2, said shell being composed 30 of sections connected at their enlarged ends and intermediate of the ends of the said shell, said enlarged ends having interengaging means combining to form an interlocking joint.

5. An audible toy comprising a hollow shell 35 having tapered annular ends, a sounding device mounted in said shell, a cord connected at its ends to the ends of said shell, said ends of the cord being adapted to be wound on the ends of the shell and unwound therefrom for revolving the shell to actuate the sounding device.

6. A toy as in claim 5, said cord being knotted intermediate of its ends and being adapted to 40 be supported at the knot for maintaining the shell in substantially a horizontal plane.

7. An audible toy comprising an elongated hollow body portion having tapered ends, a shaft 45 extending longitudinally through said body portion and protruding from the ends thereof, a sounding device fixed to said shaft and disposed in the hollow body portion, and a cord having its ends secured to the ends of said shaft.

8. A toy as in claim 7, said body portion being 50 shaped to simulate a torpedo, and a propeller rotatably mounted on one end of the shaft.

9. A toy as in claim 7, said shell being composed of conical sections, the enlarged, adjacent ends of said sections being disposed in overlapping relationship, a disk fixed to said shaft intermediate of its ends, fastening means for securing the overlapping portions of said sections to the periphery of said disk, said shaft having hubs adjacent its ends, and fastenings for securing remote ends of said conical sections to said hubs. 55

10. A musical toy comprising an elongated hollow body member, a sounding device mounted in said body member, a cord having its ends fixed to the ends of said body member, said body member having tapered ends and being formed of corresponding sections joined lengthwise, the abutting edges of said sections having outwardly projected abutting flanges, said flanges each having tongues interlocking with the flanges of the other 70 section for connecting said sections.

THOMAS I. NAKANO.
